UNITED STATES PATENT OFFICE.

OVADIO COHN, OF NEW YORK, N. Y., ASSIGNOR TO BIJOU BUTTON CO., INC., OF NEW YORK, N. Y., A CORPORATION OF NEW YORK.

MACHINE FOR MAKING CELLULOID BUTTONS.

1,296,767.

Specification of Letters Patent.

Patented Mar. 11, 1919.

Application filed April 2, 1918. Serial No. 226,298.

To all whom it may concern:

Be it known that I, OVADIO COHN, a citizen of Russia, residing at Bronx, in the county of Bronx, city and State of New York, have invented certain new and useful Improvements in Machines for Making Celluloid Buttons, of which the following is a specification.

My invention relates to a semi-automatic machine for making buttons having a celluloid top, and in particular to buttons made of a celluloid top, a cardboard stiffener and a metallic base.

Buttons of this kind are well known, and have been extensively used, and they are usually made by shaping the flat circular celluloid blank by means of heat and pressure to the required form, and then inserting a cardboard stiffener and attaching a metallic top.

Celluloid of different grades and different kinds of finish requires different degrees of heat in order to shape it properly, as well as different periods of application of the heat. In addition, the celluloid is coated with a paint of some kind to color it, and the different qualities of paints also require different treatment.

My invention relates to a semi-automatic machine which shall permit a rapid and easy manufacture of these buttons, while the operator can readily observe the process of manufacture and suitably regulate the conditions under which the buttons are made. Other objects of my invention will be pointed out in the following description and drawings which illustrate a preferred embodiment thereof.

Figure 1 is a front view of my machine.

Fig. 2 is a side view thereof.

Figs. 3, 4, 5 and 6 are rear views of the machine showing the dies in various positions.

Fig. 7 is a central vertical section through the dies, and partially shows the mechanism for moving these dies.

Fig. 8 is a view similar to Fig. 7 showing the dies in a different position.

Fig. 9 is a detail sectional view showing the shaping of the celluloid top.

Fig. 10 is a view of the metal base of the button.

Fig. 11 is a perspective view of the circu-

lar piece of celluloid from which the top of the button is shaped.

Fig. 12 is a perspective view of the stiffener for these buttons.

Fig. 13 is a detail sectional view showing how the button is completed.

The entire machine rests upon a suitable base which may be mounted on the top of a table or other convenient support. To this base the base-plate 27 is secured by means of the nuts 25 and 28, which coöperate with suitably threaded members. Upon this a lower annular die 18 is mounted. As can be seen, especially in Figs. 7 and 8, this lower die 18 is slidably mounted on the stud-die 53 which has its top surface suitably shaped so as to coöperate with the die 12. The die 18 can be slid up and down upon the stud 53, so that it can occupy the position shown in Fig. 7, or the bottom thereof can rest upon the flange of the lower end of the stud 53. The die 18 can be kept in its uppermost position by means of the dog 14, which is pivoted at 16 to the stud 17, and as is shown in Fig. 1, has a notch 15 which is adapted to fit around the top of the die 18.

At the upper part of the machine, a head 1 is moved up and down by any suitable means, such as a lever operated by the feet of the operator, or any other suitable mechanical movement which is not illustrated in the drawings, because such mechanical movements are in themselves old and form no part of my invention, and are readily within the comprehension of any person skilled in the art.

The head 1 has a circular recess therein, into which a rod 9 fits and is secured by means of the set screw 8, as shown in Fig. 2. The rod 9 is moved up and down in front of the guide-piece 2, as shown in Fig. 2. It carries the cross-head 10 which is immovably secured thereto, and may be made integral therewith. The cross-head 10 has the slide 11 connected thereto. This slide 11 moves up and down with the cross-head 10, and may also have a sliding, horizontal movement at right angles imparted thereto by any suitable means. The slide 11, as is shown most clearly in Figs. 7 and 8, has a sleeve 44 secured thereto by means of the bolt 20. To this sleeve 44, which is internally threaded, an annular die 19 is secured.

This die 19 has a plunger 40 having a recess 50, slidably mounted therein. The plunger 40 has a pin 41 secured thereto, and the cross-head 10 is suitably recessed as shown 5 in Fig. 7, so that the pin 41 can be moved to and fro. The plunger 40 fits sufficiently tightly into the interior of the die 19 to be held by friction. The cross-head 10 has a bevel surface 42, as shown in Figs. 7 and 8, 10 so that when the slide 11 is moved a sufficient distance to the left, this bevel surface 42 forces the pin 41 and the plunger 40 downwardly as is shown in Fig. 7.

At the right of the die 19, a cylindrical 15 male die 46 is secured by means of a suitably threaded head. To this die 46 a ring-shaped die 12 is secured by means of a spiral spring 13. The die 46 is suitably recessed adjacent the pin 45, which is connected to the die 12, 20 so that any rotation thereof with respect to the die 46 is prevented. The die 12 is slotted at the right hand side thereof, so that when it is lowered, it does not move the dog 14 as is shown in Fig. 9, while the die 19 25 is not slotted so that when it is lowered, it cooperates with the beveled top of the dog 14 and moves it to the right, thus releasing the die 18 and permitting it to fall to its lowermost position. The guide-piece 2 has 30 slanting slots 3 and 4 having vertical legs 5 and 6 cut therein. The slide 11 has a pin 7 secured thereto, which has a head suitably fastened therein by means of a threaded projection 21, and this fits into the slots 35 of the guide-piece 2, so that as the slide 1 1 is moved up and down, together with the cross-head 10, the slide 11 will be shifted from left to right, or vice versa, and also will be compelled to partake of the up-and- 40 down movement at certain times. To cause the pin 7 to shift from the slot 3 to the slot 4, as is shown in Fig. 3, a device is employed which is illustrated clearly in Figs. 3 to 6, inclusive. At the rear of the guide-plate 2, 45 a yoke 22 having a recess 34, is pivoted at 23. The bottom 36 of the yoke 22 has beveled faces 35. A spring 30 is secured to the projection 29 by a suitable screw or the like, and the curve of this rests upon the screw 31 50 which may be adjusted so as to cause the spring 30 to upwardly urge the cam head 32 to any desired extent. The cam head 32 has beveled faces 33 adapted to coöperate with the beveled faces 35. When the operator moves the head 1 to its uppermost position, the stud 7 is substantially on the central line between the slots 3 and 4. As this is done, one of the bevel surfaces 35 of the yoke 22 will bear against the adjacent and 55 outermost bevel edge of the cam head 32, and force it downwardly against the resistance of the spring 30. When the yoke 22 is revolved sufficiently so that the other bevel surface 35 contacts with the adjacent 60 bevel surface 33, the cam head 32 is forced

upwardly by the spring 30 with a snap, and the stored energy of the spring 30 is sufficient to throw the pin 7, together with the slide 11 sufficiently, so as to cause the pin 7 to coöperate with the slot 3, so that the 70 downward or next movement of the head 1, will cause the slide 11 to move in the opposite direction.

In this manner, as the head 1 and the cross-head 10 are moved up and down, the 75 slide 11 is alternately placed in coöoperative relation with the slots 3 and 4, so that the die 18 and stud 53 coöperate alternately with the stud 46 and the die 12, and the plunger 40 and the die 19. 80

The die 18 and stud 53 can be suitably heated by a steam jacket or by any other means which are not illustrated in the drawing as they are in themselves old and well known and form no part of my invention, 85 and are within the comprehension of any person skilled in the art. Suitable regulating means for the heat may, of course, be employed. The surfaces 33 are sufficiently separated to prevent any catching of the 90 bottom of the yoke when it is operated so as to shift the slide 11.

The operation of my device is as follows:

The operator sees that the die 18 and the stud 53 are suitably heated, and moves the 95 die 18 to its uppermost position, shown in Fig. 7, and causes it to engage in the slot 15 of the dog 14. He then takes a circular piece of celluloid 48 of the proper size, shown in Fig. 11, and places it within the 100 die 18, as shown in Fig. 7. The die 18 and the stud 53 now form what may be termed a composite female die which coöperates with the stud 46, which acts as the male die. 105

The head 1 is now moved downwardly, the pin 7 being in engagement with the slot 3, so that the celluloid blank 48 is shaped to a top 52 by the combined heat and pressure as is shown in Fig. 9. The die 12 first engages 110 the margin of the celluloid blank 48 and holds it yieldingly until it is forced by the stud 46 into the position shown in Fig. 9. The spring 13 permits the die 12 to have a relative movement with respect to the stud 115 46, as is shown in Fig. 9.

The operator now upwardly moves the head 1 whereby the yoke 22 and the cam head 32 automatically shift the slide 11, so that it will coöperate with the slot 4 of the 120 guide-piece 2. While the head 1 is in its uppermost position, the operator places the stiffener 49 on the celluloid top 52 and also places on top of this a metal base 47 having the boss 51, as is shown in Fig. 8. The 125 plunger 40 is pushed within the die 19, as it is pressed against the metal base 47, as the cross-head 10 again descends, while the die 19, coöperating with the upper bevel surface of the dog 14, moves the dog to the 130

right at the proper time, and causes the die 18 to drop to its lowermost position, so that the stud 53 now acts as a male die, while the die 19 and plunger 40 act as a composite female die. By the action of this second set of dies, the metal base 47 is forced into the celluloid top 52 whose flanges are crimped thereover so as to tightly hold it. The recess 50 in the plunger 40 fits on the boss 51, so that when the cross-head 10 is again upwardly moved, the entire completed button is carried along with it to be discharged when the bevel surface 42 acts upon the pin 41 and forces the plunger 40 out of the die 19, as is shown in Fig. 7.

I have shown a preferred embodiment of my invention but it is clear that numerous changes can be made in its details without departing from the appended claims, and 20 I do not wish to be limited to these details.

1 claim:—

1. In a machine for making buttons, having a celluloid top and a metal base, the combination of a base-plate carrying the die 53, the die 18, means for holding the die 18 so that its internal flange is above the top of the die 53, means for holding said die 18 in a second and lowered position, the slide 11 carrying the dies 46 and 12 and the 25 die 19 and the plunger 40 and means for moving the slide 11 from left to right and up and down.

2. In a machine for making buttons, having a celluloid top and a metal base, the combination of a base-plate carrying the die 53, the die 18, the dog 14, said dog 14 being adapted to hold said die 18 so that the internal flange thereof is above the top of the die 53, said die 18, when releasing the dog 35 40 45 50 14, being free to assume a lower position, and the slide 11 carrying the dies 46 and 12 and the die 19 and the plunger 40, means for moving the slide 11 from left to right and up and down, the periphery of the die 12 being so shaped that when it is lowered into the die 18, it does not move the dog 14 and the periphery of the die 19 being so shaped that when it is lowered so as to coöperate with the die 53, the dog 14 is moved out of engagement with the die 18.

3. In a machine for making buttons, having a celluloid top and a metal base, the combination of a base-plate carrying a die 53, the die 18, means for holding the die 18 so that the internal flange thereof is above the top of the die 53, the die 18 being held by gravity in a lowered position and the slide 11 carrying the dies 46 and 12, the die 19 and the plunger 40, the said die 12 being free to slide up and down on the die 46, spring means for forcing the die 12 downward with respect to die 46, and means for preventing die 12 from being forced below a predetermined part of the die 46.

4. In a machine for making buttons, hav-

ing a celluloid top and a metal base, the combination of a base-plate carrying the die 53, the die 18, means for holding the die 18 so that the internal flange thereof is above the top of the die 53, the die 18 being held by gravity in a lowered position and the slide 11 carrying the dies 46 and 12, the die 19 and the plunger 40, the said die 12 being free to slide up and down on the die 46, spring means for forcing the die 12 downward with respect to die 46 and means for preventing the die 12 from being forced below a point at which the bottom thereof is substantially on the same level with the bottom of the die 46.

5. In a machine for making buttons, having a celluloid top and a metal base, the combination of a base-plate carrying the die 53, die 18, means for holding the die 18 so that the internal flange thereof is above the top of the die 53, said die 18 being held by gravity in the lowered position and a slide 11 carrying the dies 46 and 12 and also carrying means for forcing said metallic base into a celluloid top held on the top 90 of the die 53.

6. In a machine for making buttons, having a celluloid top and a metal base, the combination of a base-plate carrying the die 53, die 18, means for holding the die 18 so that the internal flange thereof is above the top of the die 53, said die 18 being held by gravity in the lowered position and a slide 11 carrying the dies 46 and 12 and also carrying means for forcing said metallic base 100 into a celluloid top held on the top of the die 53 and for removing the completed button from the said die 53.

7. In a machine for making buttons, having a celluloid top and a metal base, the combination of the slide 10 having a recess and a beveled edge 42 and the slide 11 carrying the die 19 and the plunger 40, having a pin 41, the plunger 40 being frictionally held within the die 19, and the beveled edge 42 110 and the pin 41 being adapted to force the plunger 40 out of the die 19.

8. In a machine for making buttons, having a celluloid top and a metal base, the combination of a guide-piece 2, a member 115 provided with inclined slots 3 and 4 having vertical legs 5 and 6, respectively, cross-head 10 and the slide 11 having pin 7 and means for alternately placing the pin 7 in coöperation with the said grooves 3 and 4.

9. In a machine for making buttons, having a celluloid top and a metal base, the combination of a guide-piece 2, a member provided with inclined slots 3 and 4 having vertical legs 5 and 6, respectively, cross-head 125 10 and the slide 11 having pin 7, the yoke 22 having the slot 34 and means for alternately revolving said yoke 22 to the left and to the right, when the pin 7 is substantially at the junction of the slots 3 and 4.

10. In a machine for making buttons, having a celluloid top and a metal base, the combination of a guide-piece 2, a member provided with inclined slots 3 and 4 having 5 vertical legs 5 and 6, respectively, cross-head 10 and slide 11 having pin 7, the yoke 22 having slot 34 and spring 30 and means for

alternately revolving said yoke 22 to the left and to the right, when the pin 7 is substantially at the junction of the slots 3 and 4. 10

In testimony whereof I hereunto affix my signature.

OVADIO COHN.
